DESIGN FOR A GLOBE FOR LIGHTING FIXTURE

Stanley H. Barnes, New Rochelle, N. Y., assignor
to Gleason-Tiebout Glass Company, Maspeth,
N. Y., a corporation of New York

Application December 3, 1937, Serial No. 73,334

Term of patent 3½ years

To all whom it may concern:

Be it known that I, Stanley H. Barnes, a citizen of the United States of America and a resident of New Rochelle, in the county of Westchester and State of New York, have invented a new, original, and ornamental design for a Globe for Lighting Fixture, of which the following is a specification, reference being had to the accompanying drawing, forming a part thereof.

Figure 1 is a side elevational view partly in section of a globe for lighting fixture, showing my new design; and,

Figure 2 is a bottom plan view.

The design is characterized by an enclosing globe of the configuration shown having translucent side walls with spaced ribs and a translucent center of the bottom, said areas being illustrated by stippling; and by a transparent annular band about the center of the bottom.

I claim:

The ornamental design for a globe for lighting fixture, substantially as shown and described.

STANLEY H. BARNES.
